ROY L. VORHIES, OF LONG BEACH, CALIFORNIA, ASSIGNOR OF FIFTY PER CENT TO
E. J. WARNER, OF LONG BEACH, CALIFORNIA

MILK BOTTLE VENDING MACHINE

Application filed February 5, 1927. Serial No. 166,099.

An object of my invention is to provide a milk bottle vending machine from which a full bottle of milk cannot be obtained until an empty bottle has been deposited therein.

5 Another object is to provide a machine from which both empty and full bottles may be obtained by inserting a suitable coin in a coin controlled drawer.

10 A further object is to provide a milk bottle vending machine which returns a slug with an empty bottle, said slug serving to open a drawer when the empty bottle is returned after which the coin is returned to the customer.

15 An advantage of my machine resides in the automatic dispenser of slugs or coins when the empty bottles are returned or taken from the machine.

20 A further advantage of my machine resides in the fact that an empty bottle must always be inserted into the machine before a full bottle can be obtained.

25 A still further object is to provide a milk bottle vending machine in which all the full bottles of milk cannot be removed from the machine by the use of a single coin.

30 Other objects, advantages, and features of invention may appear from the accompanying drawings, the subjoined, detailed description, the appended claims, or in the operation of my machine.

In the drawings:—

Fig. 1 is a front elevation of my invention.

35 Fig. 2 is a fragmentary sectional view taken on line 2, 2, Fig. 1.

Fig. 3 is a fragmentary transverse sectional view of the full bottle compartment.

Fig. 4 is an enlarged side elevation of the slug controlled mechanism.

40 Fig. 5 is a front view of the same.

Fig. 6 is a sectional view taken on line 6, 6, Fig. 4.

Fig. 7 is a side view of the slug.

45 Referring more particularly to the drawing:

My invention comprises a cabinet 1 in which are provided a plurality of full bottle compartments 2, and empty bottle compartments 3. The full bottle compartment will now be described in detail.

A drawer 4 is adapted to fit into the front end of the compartment 2, said drawer being closed at the front end thereof, and opened at the rear. An opening 5 is provided in the top of the draw 4, the purpose of which will be further described. A slug controlled lock 6 is secured to the front wall of the drawer 4 and comprises a housing 7 in which a bolt 8 is slidably mounted, said bolt being held in raised position by the spring 9 surrounding a depending pin 10. A handle 11 projects through the front wall of the drawer, and said handle is provided with a lever 12 which projects through a slot 13 in the housing 7.

A slug slot 14 is provided in the housing 7 which slot is alined with an opening 15 in the front wall of the drawer 4, through which the slug 16 is adapted to pass. This slug is preferably formed with transverse slots 17 therein which fit projections 18 in the slot 14. Thus it will be seen that my slug operated mechanism can only be actuated by a particular type of slug which may be purchased in anticipation of obtaining milk therefor.

When the slug 16 drops through the slot 14 it falls upon a ledge 19 formed on the bolt 8 and the slug is now in position to be acted upon by the lever 12. As the handle 11 is now rotated the bolt 8 will be depressed and a link 20 secured to the pin 10 will be depressed. The link 20 is pivoted at 21, which pivotal arrangement causes the rear end thereof to raise out of a notch 22 when the forward end thereof is depressed as previously described.

The drawer 4 may now be pulled outwardly and this movement causes the link 20 to move over the inclined surface 23, thus further depressing the forward end thereof and permitting the slug 16 to drop through the slot 24 into a suitable receptacle. The drawer is now open and an empty bottle is dropped through the opening 5. A track 25 is positioned on the floor of the compartment 2, said track serving to raise the bottles above the floor and also enables them to slide more readily. An opening 26 is provided at the rear of the compartment 2, said opening being of sufficient size to permit the passage of one bottle. The compartment is entirely filled

with bottles and it will therefore be evident that as the drawer 4 is again pushed to closed position, as shown in Fig. 2, that the empty bottle in said drawer will engage the front 5 full bottle of milk moving the entire row of bottles rearwardly and causing the rearmost bottle to drop through the opening 26 on to the inclined board 27, whence it will slide forwardly and may be removed through the 10 opening 28 in the front of the cabinet 1. A guide 29 may be provided from the opening 26 to the inclined board 27, so that the bottles will readily fall through said opening and on to the incline. A spring actuated trap door 15 30 is provided over the opening 26 so as to prevent the escape of cold air from the compartment 2 when my vending machine is enclosed by a suitable cooling arrangement.

To prevent a person from reaching their 20 hand through the opening 5 and thus pushing the bottles in the compartment 2 rearwardly and thence, through the opening 26 to the incline 27 as previously described, I provide a slideable lock plate 31. This lock 25 plate extends over the opening 26 and is provided with a hole 32 adapted to register with said opening, and a spring 33 normally urges the plate forwardly into a position partially covering the opening 26, and when in this position no bottle can drop through said opening. A bar 34 extends forwardly from the plate 31 and is engaged by the rear edge of the drawer 4 when the drawer is in closed and locked position the bar 34 pushes the 30 35 plate 31 rearwardly thus exposing the opening 26. But as soon as the drawer 4 is unlocked and pulled outwardly the spring 33 at once partially closes said opening, thus preventing any bottles from falling there-through until the drawer has again been closed and locked.

To prevent the theft of bottles through the opening 5 when the drawer 4 is opened, I provide a movable plate 35, which plate is 40 45 slidably mounted on rails 36, said plate hanging in front of the front full bottle of milk and it will be seen that any attempt to extract this bottle will cause the plate 35 to swing upwardly effectively closing the opening 5.

Having described my invention, I claim:

1. A milk bottle vending machine comprising a cabinet, a plurality of compartments in said cabinet, drawers closing the forward 50 55 end of said compartments, said compartments having a bottle outlet at the rear thereof, the full bottles in the compartments being adapted to be actuated by an empty bottle inserted into said drawer, and means in said compartments whereby the full bottles are prevented from being removed through the drawer.

2. A milk bottle vending machine comprising a cabinet, a plurality of compartments in 60 65 said cabinet, drawers closing the forward end

of said compartments, said compartments having a bottle outlet at the rear thereof, the bottles in the compartments being adapted to be actuated by an empty bottle inserted into said drawer, and a plate slidably mounted in the compartment in front of the foremost bottle whereby the bottles are prevented from being removed through the drawer.

3. A milk bottle vending machine comprising a cabinet, a plurality of bottle compartments in the cabinet, a drawer in the forward end of said compartments, said drawers having an opening in the top thereof into which a bottle is adapted to be inserted, said compartments having an opening at the rear thereof through which the bottles are vended, said drawer being adapted on the closing thereof to push the rear-most bottle through said opening to vend the same, and a plate 80 85 slidably mounted in said compartment in front of the foremost bottle whereby removal of the bottle through the drawer is prevented.

4. A milk bottle vending machine comprising a cabinet, a plurality of bottle compartments in the cabinet, a drawer in the forward end of said compartments, said drawers having an opening in the top thereof into which a bottle is adapted to be inserted, said compartments having an opening at the rear thereof through which the bottles are vended, said drawer being adapted on the closing thereof, to push the rear-most bottle through said opening to vend the same, and a plate 90 95 slidably mounted in said compartment in front of the foremost bottle whereby removal of the bottle through the drawer is prevented, and a spring actuated door adapted to normally close the opening at the rear of the 100 compartment through which the bottles are dispensed.

5. A milk bottle vending machine comprising a cabinet, a plurality of bottle compartments in the cabinet, a drawer in the forward end of said compartments, said drawers having an opening in the top thereof into which a bottle is adapted to be inserted, said compartments having an opening at the rear thereof through which the bottles are vended, said drawer being adapted on the closing thereof, to push the rear-most bottle through said opening to vend the same, and means adapted to cover the opening at the rear of the compartment when the drawer 110 115 is pulled outwardly.

6. A milk bottle vending machine comprising a cabinet, a plurality of bottle compartments in the cabinet, a drawer in the forward end of said compartments, said drawers having an opening in the top thereof into which a bottle is adapted to be inserted, said compartments having an opening at the rear thereof through which the bottles are vended, said drawer being adapted on the closing 120 125 130

thereof, to push the rear-most bottle through said opening to vend the same, and means adapted to cover the opening at the rear of the compartment when the drawer is pulled outwardly, said last named means comprising a plate adapted to cover said opening, a spring normally urging said plate over the opening, and means adapted to be engaged by the drawer when moved into closed position to move the plate and uncover the opening.

In testimony whereof, I affix my signature.

ROY L. VÖRHIES.
